[57] CLAIM

The ornamental design for hanger for boots cloths or the like, as shown and described.

DESCRIPTION

FIG. 1 is a perspective view of a hanger for boots cloths or the like, showing my new design;

FIG. 2 is a perspective view, from the side opposite that shown in FIG. 1;

FIG. 3 is a side view taken from the right of FIG. 1;

FIG. 4 is an exploded perspective view thereof;

FIG. 5 is an exploded perspective view from the side opposite that shown in FIG. 4; and

FIG. 6 is an exploded perspective view taken from the right of FIG. 4.

FIG. 5

FIG. 6
